DESIGN FOR A VENTILATOR

Lemuel R. Boulware, Syracuse, N. Y., assignor to
Carrier Corporation, Syracuse, N. Y., a corpo-
ration of Delaware

Application November 17, 1938, Serial No. 81,177

Term of patent 7 years

To all whom it may concern:

Be it known that I, Lemuel R. Boulware, a citizen of the United States, residing at Syracuse, in the county of Onondaga and State of New York, have invented a new, original, and ornamental Design for Ventilator, of which the following is a specification, reference being had to the accompanying drawing forming part thereof.

Fig. 1 is a view in perspective of a ventilator embodying my new design;

Fig. 2 is a plan view of the ventilator of Fig. 1, and

Fig. 3 is a rear elevational view of the ventilator of Fig. 1.

I claim:

The ornamental design for a ventilator, as shown.

LEMUEL R. BOULWARE.
